UNITED STATES PATENT OFFICE.

JAMES R. BOWER AND HAROLD J. BOWER, OF SEATTLE, WASHINGTON.

STOVE.

1,163,807.

Specification of Letters Patent. Patented Dec. 14, 1915.

Application filed February 13, 1915. Serial No. 7,960.

To all whom it may concern:

Be it known that we, JAMES R. BOWER and HAROLD J. BOWER, citizens of the United States, residing at Seattle, in the county of King and State of Washington, have invented certain new and useful Improvements in Stoves, of which the following is a specification.

The object of our invention is to improve 10 the construction of stoves in various particulars so as to render the same more convenient to use, more efficient in use, and whereby the articles being cooked therein may be inspected without opening the doors 15 of the oven, etc.

With these and other ends in view, the invention consists, first, in the provision of glazed doors at opposite sides of the stove compartments; second, in ventilating devices for the escape or withdrawal of the 20 unconsumed gases or products thereof and odors due to cooking; third, in providing revolving platforms for the support of articles being cooked so as to carry the latter 25 in various rotary positions within the ovens in order that they may be more uniformly baked or roasted; fourth, providing in certain of the supports receptacles for absorbent material whose office is to collect drippings which may overflow from the cooking 30 utensils carried by the supports and, finally, in the novel construction, arrangement and combination of the several parts, as will be hereinafter described and claimed.

35 In the accompanying drawings, Figure 1 is a view partly in front elevation and partly in transverse vertical section, of a stove embodying our improvements. Fig. 2 is a longitudinal vertical section of the 40 same. Fig. 3 is a horizontal section taken substantially through 3—3 of Figs. 1 and 2. Figs. 4 and 5 are vertical sectional views through 4—4 and 5—5 of Fig. 3.

In the drawings, the reference numerals 45 10 designate the ends, 11 the top and 12 the bottom of the stove casing. This casing is divided interiorly by a vertical partition 13 and by horizontal partitions 14 and 15 to afford broiling compartments 16 and 16¹ at 50 the bottom, combustion chambers 17 and 17¹ immediately below the stove top 11, and ovens 18 and 18¹ between said combustion chambers and the broiling compartments.

The ovens 18 and 18¹ are provided on 55 their side walls with bracket strips 19 to support removable grills or shelves 20. In the

front of the compartments and ovens, respectively, are doors 21 and 22 which are formed with transparent panels 21¹ and 22¹ such as of glass or mica. Also in the back 60 of the stove are openings provided with panes of glass or mica, as indicated by 23, to admit light and to enable the interiors of the compartments or ovens to be viewed from the rear.

24 represent gas burners of any suitable type extending into the broiling compartments and in proximity to the partitions 15 to allow space therebelow for the insertion of pans containing meat for broiling.

Gas burners are provided in the combustion chambers 17 and 17¹ and are each comprised, as shown in Fig. 2, of a perforated terminal tube 25 connected by a bend 25¹ with a flaring air inlet 25² which extends 70 into an oven.

26 represents the nozzle of a fuel gas-supply pipe 26¹ which enters the tube 25.

By thus forming a burner with the air inlet leading into an oven, the air for combustion purposes is drawn with other gases or smoke due to cooking from the oven to ventilate the same. Supplementary to the ventilation due to the above described gas burner, we provide for each oven a conical 80 tube 27 (Fig. 2) having its smaller end directed toward the chimney pipe 28 which becomes operative by reason of the suction 85 created by the currents flowing into the chimney pipe.

Within the oven 18 is a platform formed of an annular plate 28 and a circular plate 29, the latter having, as shown in Fig. 5, its upper surface in a plane slightly below the upper surface of the annular plate. Depending from the respective plates are annular ribs 28¹ and 29¹ which serve as track elements with respect to grooved wheels 30 and 30¹ for the one and 31 and 31¹ for the other rib. These wheels have their axles 100 journaled in chairs 30² and 31² which are secured to the partition 15 therebelow. There are provided three symmetrically disposed wheels for each of said plates and are disposed to have those indicated by 30¹ and 105 31¹ positioned at diametrically opposite sides of the respective plates and mounted on a horizontal shaft 32 whereby the rotation of the shaft will, through the medium of the referred to wheels, impart rotary motion to 110 the plates in opposite directions. 33 represents a pulley on said shaft for an endless

belt 34 (Fig. 1) driven from a motor 35. About the plate 28 is a gutter 36 to receive granulated charcoal or other material which will absorb liquids which may overflow from 5 a pan or pans placed on the plate and thus prevent its spilling on the relatively hot oven floor or partition 15.

The object of having plates 28 and 29 rotate in contrary directions is to make a 10 more effective display of articles within the oven 18 when the stove, for exhibition or advertising purposes, is placed in the window or an exposed position of a restaurant, or the like. Under such conditions, a large 15 dish may be placed upon the central plate 29 and a number of smaller dishes distributed over the outer plate 28.

In the other oven, 18¹, we provide a rotary spider constituted of a hub 37 with 20 radial arms 38 integral therewith and arms 38¹ which are hingedly connected to the hub by pivotal pins 39 for vertical swinging movements so that the wheels 40 hereinafter referred to may at all times properly engage 25 the tracks also referred to hereinafter. The arms 38 and 38¹ have journaled thereon grooved supporting wheels 40 and 40¹, whereof the latter are located at greater distances than the other wheels 40 from the 30 axis of the spider. The arms 38 and 38¹ are respectively provided with branches 41 and 41¹ on which are rotatably mounted grooved wheels 42 and 42¹ of less diameters than the associated wheels 40 and 40¹. The 35 wheels of each arm are disposed symmetrically about a focal point and each such group of wheels is arranged to receive in the wheel grooves a ridge 43 depending from a plate 43¹. These plates are advantageously each 40 provided with a peripheral gutter 36¹ having an office similar to that of the afore-described gutter 36 of the plate 28. The spider is detachably connected to an upright spindle 44 (Fig. 1) having at its lower 45 end a bevel gear-wheel 45 in mesh with a like wheel 46 provided on a horizontal shaft 46¹. This shaft is driven from said motor by an endless belt 47 passing about a pulley 48 upon the shaft. When the spindle is thus 50 rotated, the wheels 40 and 40¹ track upon the floor of oven 18¹ and thereby impart rotary movements to the superposed plates 43. By reason, however, of the wheels 40 and 40¹ being located at different positions 55 from the axes of their revolution and engaging the plate-ridges at the inner and outer diametrically opposite sides of the alternate plates, the same are caused to rotate in contrary directions in their orbital 60 travel about the axis of the spider.

Pans or dishes are placed on the various plates 43 and furnish an attractive display of the same as they perform their several movements. The rotary plates of both ovens 65 not only serve to show the dishes, etc., which

may be supported thereon, but also insure their being cooked more uniformly by rotating and revolving to expose the food from all sides to the hotter portions of the ovens.

In operation, the articles to be cooked 70 are placed in the broiling compartments or the ovens with the appropriate burners employed. For a broiling compartment the burners 24 would be utilized, while for the ovens such burners and the burners 25 would 75 be used according as to whether an underneath heat, a top heat or both are desirable. Pans containing articles to be baked in the ovens 18 or 18¹ are deposited on the plates of the respective ovens, whereupon the same 80 are rotated or revolved through the afore-described driving mechanism therefor. While being cooked, or subsequently, the articles may be inspected through the glass from either the front or rear of the stove. 85 After cooking, the heat may be reduced or stopped by suitably regulating the burners, without interrupting the movements of the articles.

What we claim as our invention, is— 90

1. In a stove-oven, a plurality of rotatable plates within the oven, wheels supporting said plates, a shaft extending into the oven and operatively connected to a wheel for each of the plates, said wheels being arranged so that the rotation of the shaft in either direction will cause said plates to be simultaneously rotated in opposite directions from each other. 95

2. In a stove-oven, an annular plate, a second plate disposed concentrically thereof, a circular rib depending from the underside of each of said plates, grooved wheels for engaging the respective ribs for supporting the plates, and means to rotate the plates in 105 opposite directions through the medium of said wheels. 100

3. In a stove-oven, a support for a pan, means to revolvably move said support within the oven, and means actuated by the aforesaid means whereby the support is rotated during its orbital travel. 110

4. In a stove-oven, a rotary spider, said spider being formed with a hub, a plurality of arms connected to the hub, wheels rotatably mounted on said arms, a plate supported by the wheels of each arm, and means to rotate the spider, one of the wheels of each arm being adapted to track on the bottom of the oven and disposed so that as the 115 spider turns, the alternate plates are rotated in opposite directions. 120

5. In a stove-oven, a rotary spider, said spider being formed with a hub, a plurality of arms rigid with the hub, a plurality of arms hingedly connected to the hub and disposed to alternate with the first-named arms, wheels rotatably mounted on said arms, a plate supported by the wheels of each arm, and means to rotate the spider, one 125 130

of the wheels of each arm being adapted to track on the bottom of the oven and disposed so that as the spider turns the alternate plates are rotated in opposite directions.

5 6. In a stove oven, a carrier rotatable about an axis in said oven, pan supports located on said carrier and rotatable thereon, the axes of the pan supports being spaced from the axis of the carrier, and
10 means to cause rotation of the pan supports during the rotation of the carrier.

7. In a stove oven, the combination with an oven floor, of a spider rotatable above

said floor, pan supporting means carried by the spider and arranged to revolve about ¹⁵ axes spaced from the axis of the spider, and means to rotate the spider and simultaneously rotate each pan supporting means about its axis.

Signed at Seattle Wash., this 5th day of 20 February, 1915.
